Primary Examiner — Mitchell I. Siegel

(74) Attorney, Agent, or Firm — Banner & Witcoff, Ltd.

(57) **CLAIM**

The ornamental design for a sporting implement, as shown and described.

DESCRIPTION

FIG. 1 is a top, left, rear perspective view of a sporting implement showing our new design;

FIG. 2 is a rear view thereof;

FIG. 3 is a front view thereof;

FIG. 4 is a top view thereof;

FIG. 5 is a bottom view thereof;

FIG. 6 is a left side view thereof;

FIG. 7 is a right side view thereof; and,

FIG. 8 is a cross-sectional view at 8-8 in FIG. 2 thereof.

The even-length broken lines showing the remainder of the sporting implement represent unclaimed subject matter and form no part of the claimed design.

1 Claim, 6 Drawing Sheets(56)
